PORTABLE REFRIGERATOR CABINET

Delmar D. Rhoads, 3112 Oakwood Drive,
Fort Wayne, Ind.

Filed Sept. 10, 1958, Ser. No. 52,590

Term of patent 14 years

(Cl. D14—3)

FIG.1

The rear not shown is substantially plain.

I claim:

The ornamental design for a portable refrigerator cabinet, as shown and described.
